OIL TIGHT FLANGE FOR SHOCKPROOF
X-RAY UNITS

Paul Ernest Sacks, Cedar Grove, N. J., assignor,
by mesne assignments, to Westinghouse Electric
and Manufacturing Company, East Pittsburgh,
Pa., a corporation of Pennsylvania

Application March 28, 1933, Serial No. 663,136

7 Claims. (Cl. 250—34)

My invention relates to X-ray apparatus and particularly to shockproof apparatus and X-ray tubes therefor wherein the danger of accidentally contacting any of the high voltage parts of the device is obviated.

Devices of this general type are known to the prior art in which the X-ray tube and the high potential source of energy therefor is encased within a housing with both tube and transformer immersed in a body of insulating and cooling material having a higher di-electric strength than air, such as oil. By the utilization of a material having a higher di-electric strength than air the spacing between all high tension carrying parts is considerably lessened over that required for the same applied voltage when operating in air, thus resulting in an X-ray tube materially shortened in length due to a smaller spacing between the high tension electrode terminals.

Moreover, during operation of the device the X-ray tube generates appreciable heat which is dissipated by the envelope itself to the surrounding insulating and cooling medium and in addition it may be more readily dissipated by providing the anode stem of the tube with a cooling radiator likewise immersed in this body. A rugged and compact X-ray unit of a portable nature accordingly results which is free from the danger of electrical shocks to operator or patient and which is capable of supplying the X-ray tube with relatively high electrical energy.

In these devices, however, an objectionable feature is inherent due to the necessity for the X-rays radiating from the tube to penetrate the insulating and cooling medium surrounding the tube. The X-rays in passing through this medium are affected to a great extent due to the oil or medium acting as a filter thus materially altering the quality of the X-rays to which a patient or a sensitized film is subjected.

My present invention constitutes an improvement in the X-ray tube support for shock proof apparatus as shown and described in the co-pending application of Montford Morrison, Serial No. 654,654, filed February 1, 1933 which has matured into Patent #1,968,051 dated July 31, 1934 in which all of the essential features requisite in shock proof X-ray apparatus are retained by preventing accidental shocks resulting to patient or operator through the immersion of all high tension terminals and carrying parts in a body of cooling and insulating material. Moreover, I utilize a fore-shortened tube due to the cooling and insulating material having a higher di-electric strength than air, but obviate the ob-

jectionable feature of allowing the oil surrounding these high tension carrying parts to act as a filter for the X-rays emanating from the tube.

My X-ray tube is provided with a rigid support forming substantially a part of the tube thus rendering it readily adaptable to a shock proof apparatus by enabling the tube as a unit to be secured to the apparatus and form an oil tight seal therewith. By disposing the ray projecting portion of the envelope, through which the X-rays emanate from the anode target during energization of the tube, exteriorly of the casing or tank encasing the high tension parts of the apparatus when the tube is secured thereto the quality of the X-rays is in no way affected by extrinsic obstacles.

For a better understanding of the novel features of my present invention reference may be had to the accompanying drawings wherein;

Figure 1 is a sectional view of a shock proof unit constructed in accordance with my invention with a portion of the apparatus shown in diagrammatical form for the purpose of simplicity;

Figure 2 is an elevational view in section on an enlarged scale of the tube supporting structure shown in Figure 1 with a part broken away to better illustrate the several parts;

Figure 3 is an elevational view in section on a slightly enlarged scale of a modification of the tube supporting structure of Figure 1; and

Figure 4 is an elevational view in section on a slightly enlarged scale of still another modification of the tube supporting structure with a part broken away to better illustrate the several parts.

Referring now to the drawings in detail I have shown a casing 5 which may be of a light and durable metal suitably grounded as at 6. A high tension transformer 7 diagrammatically illustrated having a primary winding 8 and a high tension secondary winding 9 is housed within the casing and immersed in an insulating and cooling material, such as oil 11. The primary winding 8 of the high tension transformer receives electrical energy from a suitable source of alternating current of the usual commercial potential (not shown) through a pair of conductors 12 and 13 passing through a suitable insulating block or terminal 14 provided in the wall of the casing.

An X-ray tube having a vitreous evacuated envelope 15, an anode 16 and a thermionic cathode 17, is secured to the casing 5 in a manner to be hereinafter more fully described, with the

ray projecting portion of the envelope disposed exteriorly of the casing and the remainder of the envelope disposed interiorly of the casing and immersed in a body of cooling and insulating material 11.

The anode 16 of the X-ray tube is provided with a cooling radiator 18 which is likewise immersed in the insulating and cooling medium for the purpose of transmitting the heat generated during 10 operation of the tube to this latter medium and in addition the envelope 15 likewise dissipates appreciable heat to the surrounding medium.

The thermionic cathode 17 is adapted to receive heating current from a suitable source of 15 low tension electrical energy, such as a transformer 19, which may be housed within the casing 5 or remotely disposed therefrom upon a suitable control stand which supports the unit contained within the casing 5. By disposing the 20 low tension transformer exteriorly of the casing 5 the latter is materially reduced in weight.

The low tension cathode heating transformer is provided with a primary winding 21 and this winding is energized by means of a pair of conductors 22 and 23 which may be connected to the 25 same commercial source of supply as the conductors 12 and 13. A low tension secondary winding 24 of the transformer 19 supplies heating current to the cathode 17 of the X-ray tube 30 through a conductor 25 which extends to one of the cathode terminals 26 of the X-ray tube disposed exteriorly of the envelope and casing. The other end of the secondary winding 24 is connected to the grounded metallic casing 5 through 35 a conductor 27 and as the remaining cathode terminal 28 is in metallic connection with the casing 5 a circuit to the cathode 17 is thus completed.

One end of the high tension secondary winding 9 is connected to the anode terminal which 40 constitutes the radiator 18, by means of a conductor 29 disposed within the casing, and the remaining end of the high tension secondary winding is connected through a conductor 31 to 45 the grounded metallic casing 5 and is thus supplied to the cathode terminal 28 which, as before stated, is in metallic connection with the casing 5.

In the operation of my shock proof unit a 50 control stand is normally employed which contains the switches for connecting the primary winding 8 of the high tension transformer 7 and the primary winding 21 of the low tension heating transformer 19 to the commercial source of supply. The X-ray tube 15 is supported by the container 55 5 as shown in Figures 1 and 2 by means of a metallic flange 32 surrounding the envelope 15 and rigidly secured thereto, which may be composed of substantially the same metal as that of the casing 5. This flange may be secured to the 60 casing 5 by any suitable means, such for example as studs 33 and nuts 34 with a gasket 35 interposed between the flange and the casing for the purpose of making an oil tight connection therebetween. Although this flange 32 may be cast in 65 one piece or otherwise formed I prefer, in the interest of economy of manufacture, to provide the same with an annular portion 36 which fits tightly within a groove 37 provided in the flange thus forming an integral member. The annular portion 36 is threaded internally as at 38 and a collar 39 having external threads 41 is arranged to engage the threaded portion 38 of the annular portion 36.

70 75 The flange 32 is provided with a shoulder

portion 42 extending slightly over the point of connection of the annular portion thereof. A plurality of oil resisting yieldable rings 43 are interposed between the shoulder portion 42 and the collar 39. A metallic ring 44 surrounds the envelope 15 of the X-ray tube and is in contact with the collar 39. This collar is provided with grooves 45 which may be engaged by a suitable tool for the purpose of rotating the same, thus forcing the metallic ring 44 against the oil resisting rings 43. The pressure thus exerted by the threaded engagement of the collar 39 with the annular portion 36 of the flange 32 compresses the oil resisting yieldable rings 43 and forces the latter in a radial direction into firm frictional engagement with the inner walls of the annular portion 36 and the envelope of the X-ray tube 15. An oil tight connection is accordingly formed between the envelope and the flange which forms a rigid support for the entire X-ray tube with the flange constituting substantially a part of the tube. The cathode terminal 26 to which the conductor 25 is connected is arranged to engage a spring clip or contact terminal 46 supported by an insulating block 47 with the latter in turn rigidly secured to the flange 32 thus completely insulating this spring clip and the cathode terminal 26 from the flange 32 and metallic casing 5.

The cathode terminal 26 is likewise arranged to engage a similar spring clip contact terminal 48 but this latter terminal is rigidly connected to the flange member 32 and, as this latter is in metallic connection with the casing 5 by means of the studs 33 and nuts 34, an electrical connection is accordingly made. This transmits the high and low tension energy to the cathode terminal 28, as one side of the high voltage secondary winding and the low tension secondary winding is connected to the metallic casing 5, as 40 before stated.

In addition to the oil resisting yieldable rings 43 I may, if desired, apply an oil resisting cement, such as 49, between the shoulder portion 42 of the flange 32 and the envelope 15 of the 45 X-ray tube and also between the collar 39 and the envelope 15, if desired, thus preventing any seepage of oil in the event the rings 43 become saturated. These rings 43, however, are composed of oil resisting composition which are not 50 deleteriously affected after long usage or contact with oil and accordingly an oil tight connection is always maintained between the flange member and the X-ray tube.

Referring now more particularly to Figure 3 55 I have shown the X-ray tube 15 supported by a similar flange 32 likewise provided with an annular portion 36 which fits within a groove 37 in the flange member 32 to form an integral unit in the same manner as described relative to Figures 60 1 and 2. In this particular modification I coat the envelope of the X-ray tube with a thin layer of metal 51, such as copper or tin. This may be applied in any suitable manner so that the same 65 adheres to the envelope.

In order to unite the X-ray tube with the supporting flange I fuse a still further metal 52 to the annular portion of the flange and the layer of metal 51. This metal 52 naturally has a lower 70 fusion temperature than either the metal 51 or the metallic flange 32 and must be applied with care, otherwise the heat in applying the metal 52 will cause the metal 51 to peel or otherwise become disengaged from the envelope 15. In all other respects this modification is identical with 75

Figures 1 and 2 and after the tube is provided with the flange it may be secured to the casing by an oil tight connection, as previously described.

In Figure 4 I have shown still another method 5 of constructing the X-ray tube support. Again I provide a flange member 32 together with an annular portion 36, but in this particular embodiment this annular portion is slightly tapered, as at 53. A plurality of oil resisting yieldable 10 rings 43 are again interposed between the envelope and the annular flange portion as in Figures 1 and 2. In constructing the flange member of this modification I surround the annular portion 36 with a loose collar (not shown) hav- 15 ing an internal diameter slightly greater than that of the largest portion of the annular flange 36. By inverting the X-ray tube with the flange member surrounding the envelope thereof and the oil resisting rings 43 in the position shown in 20 this figure, I then cast another collar 54 between the loose collar which constitutes a form or mold therefor and the annular ring portion 36. The molten metal accordingly flows into contact with the flange 32 and also between the envelope 15 and the annular portion 36 into contact with the oil resisting rings 43. This molten metal is suf- 25 ficiently cooled after which the loose collar or mold may be removed. This accordingly forms an integral unit for supporting the envelope of the 30 X-ray tube directly by the flange member 32.

Again I may apply an oil resisting cement 49 between the envelope 15 and the flange 32 to prevent any seepage of oil between the flange member and the X-ray tube. In this modification 35 the flange with the X-ray tube supported thereby is secured to the casing 5 by a stud and nut connection in the same manner as described relative to the preceding modification.

Accordingly in all modifications shown the tube 40 may be readily removed for replacement or repair without disturbing any other portions of the apparatus. In the type of X-ray tube shown the X-rays emanate from the bulbous end of the envelope adjacent the cathode, and by this par- 45 ticular construction the X-rays emanate from the tube during operation thereof exteriorly of the casing where it is entirely free from oil which would otherwise act as a filter for the X-rays and affect the quality of the rays generated. The 50 remainder of the envelope 15, together with the anode terminal and the cooling radiator 18, is disposed interiorly of the casing and thus im- mersed in the cooling and insulating material.

The heat generated during operation of the 55 tube is transmitted to the cooling and insulating medium through the walls of the envelope, as well as by the radiator 18, resulting in effective cooling of the entire tube. Furthermore, all high tension parts carrying a potential above ground, 60 such for example as the anode terminal or radiator 18, and the conductor 29 are immersed in the cooling and insulating medium having a higher di-electric strength than air. This enables the spacing between the electrode terminals and all 65 high tension carrying parts to be considerably lessened for that required for the same applied voltage in air. Moreover, an X-ray tube considerably shortened in length results making a compact shockproof unit.

In view of the foregoing it becomes readily 70 manifested that I have provided a shockproof unit that is rugged and compact in construction and in which the possibilities of accidental shocks resulting to patient or operator is entirely eliminated.

Although the greater portion of the X-ray tube when secured to the casing is immersed in the cooling and insulating medium the ray projecting portion of the envelope through which X-rays emanate is disposed exteriorly of the casing and medium, thus removing all obstacles which may in any way affect the quality of the X-rays projected upon a patient or sensitized film.

Having described several embodiments of my invention I do not desire to be limited thereto as various other modifications of the same may be made without departing from the spirit and scope of the invention as set forth in the appended claims.

What is claimed is:

1. In an X-ray apparatus, the combination of 15 a casing provided with a source of high potential electrical energy therein, an insulating and cooling medium enveloping said high potential source, an X-ray tube provided with an evacuated envelope having an anode and cathode therein and energizable by said high tension source, means surrounding the envelope of said tube and secured to said casing to form an oil tight seal therewith, means surrounding the envelope of 20 said tube and engageable with said first mentioned means, and yieldable means interposed between both of said aforementioned means and adapted to be forced into frictional contact with the envelope of said tube and said first mentioned 25 means to form an oil tight seal therewith by the engagement of said second mentioned means with said first mentioned means.

2. In an X-ray apparatus, the combination of 30 a casing provided with a source of high potential electrical energy therein, an insulating and cooling medium enveloping said high potential source, an X-ray tube provided with an evacuated envelope having an anode and cathode therein and energizable by said high tension source, means 35 secured to said casing forming an oil tight seal therewith and surrounding the envelope of said tube, for supporting the latter with the ray projecting portion of said envelope and cathode terminals thereof disposed exteriorly of said casing 40 and the remainder of said envelope and anode terminal disposed interiorly of said casing, means surrounding the envelope of said tube and engageable with said first mentioned means, and yieldable means interposed between both of said 45 aforementioned means and operable to secure the envelope of said tube to said first mentioned means and form an oil tight seal therewith by compression of said yieldable means upon engagement of said second mentioned means with 50 said first mentioned means.

3. In an X-ray apparatus, the combination of 55 a casing provided with a source of high potential energy therein, an insulating and cooling medium enveloping said high potential source, an X-ray tube provided with an evacuated envelope having an anode and cathode therein and energizable by said high potential source, and means secured to the envelope of said tube for supporting the 60 same from said casing with the ray projecting portion of said envelope disposed exteriorly of said casing and the remainder thereof disposed internally of said casing immersed in said insulating and cooling medium comprising a flange 65 surrounding the envelope of said tube having an internally threaded annular portion and forming an oil tight seal with said casing, an externally threaded collar surrounding the envelope of said tube engageable with the threaded portion of 70 75

5 said flange, and a plurality of oil resisting yieldable rings interposed between said flange and said collar, and adapted to be forced into frictional engagement with the envelope of said tube and
5 said flange to form an oil tight seal therewith upon the engagement of said collar with said flange.

10 4. In an X-ray apparatus, the combination of a casing provided with a source of high potential electrical energy therein, an insulating and cooling medium enveloping said high potential source, an X-ray tube provided with an evacuated envelope having an anode and cathode therein and energizable by said high tension source, a
15 flange surrounding the envelope of said tube and secured to said container by an oil tight connection for supporting said tube with the ray projecting portion of the envelope of said tube disposed exteriorly of said container and the remainder of the envelope of said tube disposed interiorly of said container immersed in said insulating and cooling medium, said flange provided with an annular threaded portion and an annular shoulder, an externally threaded collar surrounding the envelope of said tube and engageable with the threaded portion of said flange, and a plurality of oil resisting rings surrounding the envelope of said tube and interposed between the annular shoulder of said flange and said collar, said
30 rings being pressed against the shoulder portion of said flange by the engagement of said collar with said flange, and forced radially into frictional engagement with the latter and the envelope of said tube to form an oil tight connection
35 between said tube and said flange.

40 5. In an X-ray apparatus, the combination of a casing provided with a source of high potential energy therein, an insulating and cooling medium enveloping said high potential source, an X-ray tube provided with an evacuated envelope having an anode and cathode therein and energizable by said high potential source, and means secured

5 to the envelope of said tube for supporting the same from said casing with the ray projecting portion of said envelope disposed exteriorly of said casing and the remainder thereof disposed internally of said casing immersed in said insulating and cooling medium comprising a flange surrounding the envelope of said tube having a tapering annular portion and forming an oil tight seal with said casing, a metallic collar cast around the envelope of said tube and the annular portion of said flange to unite the two and form a support for said tube, and means interposed between the envelope of said tube and said flange to prevent the flow of molten metal through the annular portion of said flange during casting of said collar.

10 6. The combination with an electron discharge device having an evacuated vitreous envelope, of means for securing said device to a suitable support comprising an annular flange surrounding the envelope of said device, an annular collar surrounding said envelope and engageable with said annular flange, and yieldable oil resisting means interposed between said annular collar and said flange and adapted to be forced into frictional engagement with the envelope of said device and said flange by the engagement of said collar with said flange.

15 7. An electron discharge device having an evacuated envelope provided with electrodes therein, an annular flange surrounding said tube and, means for securing said flange to said tube to form an oil tight seal, said means comprising a metallic collar cast in molten state around the interior and exterior of said flange and around said tube, and an oil resisting material disposed between said flange and said tube to maintain the molten metal between said tube and flange until cooled and for preventing any seepage of oil
20 therebetween.

25 30 35 40 PAUL ERNEST SACKS.
